UNITED STATES PATENT OFFICE.

EGGBERT M. TINGLEY, OF PITTSBURG, PENNSYLVANIA, ASSIGNOR TO THE WESTINGHOUSE ELECTRIC AND MANUFACTURING COMPANY, OF PENNSYLVANIA.

AUTOMATIC ELECTROMAGNETIC FRICTION-BRAKE.

SPECIFICATION forming part of Letters Patent No. 633,969, dated September 26, 1899.

Application filed May 18, 1899. Serial No. 717,330. (No model.)

To all whom it may concern:

Be it known that I, EGGBERT M. TINGLEY, a citizen of the United States, residing at Pittsburgh, in the county of Allegheny and State 5 of Pennsylvania, have invented a new and useful Improvement in Automatic Friction-Brakes, (Case No. 820,) of which the following is a specification.

My invention relates to brakes for rotating 10 shafts or axles; and it has for its object to provide a device of this character for use in connection with electric motors which shall act automatically and effectively to stop the rotation of the motor-shaft when the supply- 15 circuit is opened and which shall be withdrawn by the closing of such supply-circuit.

In the accompanying drawings, Figure 1 is a view, partially in end elevation and partially in section, of my brake setting and releasing mechanism; and Fig. 2 is an end elevation of the motor-shaft, brake-disks, and supports, parts of the disks being broken away to more clearly show the construction. Fig. 3 is a vertical longitudinal section through 25 the brake and its setting and releasing mechanism and showing a portion of an electric motor to which the brake is applied. Fig. 4 is a horizontal longitudinal section of the apparatus shown in Fig. 3.

The electric motor 1 here shown is of the two-phase induction type, the induced or secondary member being mounted upon a shaft 3. The inducing or primary member has a frame or casing 4, which affords a support 35 for the brake and its operating mechanism. My invention may, however, be applied to a polyphase alternating-current motor of different type, the machine shown being merely illustrative of any suitable motor which it 40 may be desired to employ.

The casing 5 for the brake is provided with supporting-arms 6, which are bolted to the frame or casing 4 of the motor. This casing 5 surrounds the end of the shaft 3 and includes within it a hub 7, that is keyed or splined to the shaft. The inner periphery of the casing 5 is provided with longitudinal grooves 8, four such grooves being shown in the drawings, though a greater or a less number 50 may be employed, if desired, and the hub

7 is provided with similar longitudinal grooves 9. A number of annular plates 10 and 11 surround the hub 7 within the casing 5, the plates 10 having lugs 10^a on their external peripheries extending into the grooves 8 in the casing. The plates 11 alternate with the plates 10 and have lugs 11^a on their inner peripheries, which are located in longitudinal grooves 9 in the hub 7. It will be understood that the plates 10 and 11 may be provided with 60 notches and the parts 5 and 7 with co-operating ribs, if desired, this being a mere reversal of what is shown. The hub 7 is also surrounded inside the casing 5 by an annular follower-plate 12 of such dimensions that 65 the shaft and axle are free to turn independently thereof, except when it is pressed against the outer brake-plate 10 by means to be hereinafter described.

A two-part frame 13, in which is fastened 70 a laminated core 14 by means of bolts 15, is rigidly connected to the follower-plate 12 by means of arms 16 and bolts 17, which extend through the arms and into the plate 12. A second two-part frame 18 of similar construction and containing a laminated core 19, clamped in the frame by means of bolts 20, is rigidly connected to the first-named frame 75 by arms 21, integral with the latter and bolted to the former. The frame 18 is provided at 80 its top and bottom with extensions 22, having openings for the reception of two guide-rods 23, the outer ends of these guide-rods being seated in sockets in lugs 24, formed on the inner side of an end plate 25. Two frames 26 85 and 27, similar in form and dimensions to the frames above described, are also provided, the outer one, 27, being bolted to the end plate 25 and containing a laminated core 28, fastened 90 therein by means of bolts 29. The inner end 90 of the core 28 is separated from the outer end of the core 19 by air-spaces 30, as is clearly shown in Figs. 3 and 4. The frame 26 contains a laminated core 31, clamped within it by means of bolts 32, the inner end of such 95 core being separated from the outer end of the core 14 by air-spaces 33. The supporting-frame 26 is rigidly connected to the casing 5 by means of arms 34, which are formed integral with the frame and bolted to the cas- 100

ing, as clearly shown in Fig. 4. The frame 26 is also rigidly fastened to the frame 27 by means of bolts 35, also shown in Fig. 4.

Interposed between the follower-plate 12 5 and the frame 27 are two coiled springs 36 and 37, each of which is supported at its ends by pins 38 and 39, projecting, respectively, from brackets bolted to the follower-plate 12 and to the frame 27.

10 Located between the two core-sections 14 and 31 is a magnet-coil 40, and located between the two core-sections 19 and 28 is a second magnet-coil 41. When a two-phase alternating-current motor is employed, the 15 current supplied to one of these coils will generally differ in phase by approximately ninety degrees from that supplied to the other, the leads to the coils extending through a passage 42 to the block 43 on the top of the casing 5, this block being provided with binding-screws, as shown in Fig. 3. The movable portions of the magnet-cores are, in effect, armatures and may be so designated. The two coils 40 and 41 are energized by currents which 20 differ in phase in order that the magnetic pull exerted by the magnets when active may be at all times greater than the force exerted by the springs 36. If a three-phase motor be employed, three pairs of core-sections and 25 three coils may be employed, or by suitably winding and connecting the coils—as indicated, for example, in Patent No. 521,051, granted to C. F. Scott June 5, 1894—two magnets will suffice in all cases.

30 35 The utilization of multiphase currents for the purpose of securing a constant magnetic pull I do not claim, broadly, as of my invention; but I believe the arrangement of a plurality of polyphase magnets in tandem, as 40 shown, whereby they exert a magnetic pull in the same line, to be original with me.

The brake setting and releasing mechanism above described is inclosed by the casing 5 and end plate 25 in conjunction with a tubular casing 44, connecting the two.

45 The operation of the apparatus is as follows: When the circuits through which currents are supplied to the motor are closed, the currents flowing to the motor will pass through 50 the magnet-coils either in shunt or in series, preferably the former, and since the core-sections 28 and 31 are stationary the armatures 14 and 19 will be drawn toward the stationary sections against the action of the springs 36 and 37, thus moving the follower-plate 12 55 outward. The brake-disks 11 will then be free to rotate, and the operation of the motor will not be impeded so long as the supply-circuits remain closed.

60 The magnet-core sections are so constructed and arranged that the contiguous faces are always in mechanical contact when the current is on in order to avoid the destructive vibration of the cores which would otherwise 65 obtain. If the supply-circuits are opened by the controlling-switch, however, in order to

stop the mechanism operated by the motor, the magnets will be deenergized and the coiled springs 36 and 37 will instantly force the follower-plate against the end disk 10, 70 and since the disks 10 are held from rotation by reason of the lugs 10^a and grooves 8 in the casing 5 the movement of the motor-shaft will be arrested and held stationary until the supply-circuits are again closed.

75 The mechanism constituting my invention is especially adapted for use in connection with motors for operating cranes and hoisting machinery; but I do not desire to limit my invention to use in connection with motors employed for any specific class of work, nor do I intend to limit my invention to the specific details of construction shown and described either as regards the brake mechanism or the mechanism for setting and releasing it.

80 I claim as my invention—

1. A brake for polyphase alternating-current motors comprising a plurality of non-rotatable friction-plates, a plurality of plates 90 fastened to the motor-shaft and alternating with the non-rotatable plates, means for normally holding said plates in braking engagement, a plurality of magnets energized by out-of-phase currents, an armature for each 95 magnet, and a connection between the same and the brake-setting device, said magnets being arranged in tandem so that they exert a pull in the same line when energized.

2. The combination with a brake and a 100 constantly-acting brake-setting means, of a plurality of magnet-coils energized by polyphase currents, a movable core-section or armature for each coil and means for connecting the same to the brake-setting means to oppose 105 the normal action of said means, said coils and armatures being arranged in tandem so as to exert a straight-line pull when energized.

3. The combination with a friction-brake 110 and springs for setting the same, of a plurality of coils arranged in tandem to be energized by out-of-phase currents, a divided core for each of said coils, one portion of each core being stationary, the other portions being 115 connected to the brake-setting means, whereby said movable core portions are drawn toward the stationary portions in the same line, in opposition to the action of the springs, when the coils are energized.

120 4. In a brake for electric motors, the combination with a set of plates rotatable with the motor-shaft and non-rotatable plates alternating therewith, of a brake-setting block adjacent to the outer plate at one side, means 125 for pressing said block toward said plates, and a plurality of coils arranged in tandem and having two-part cores, one part of each core being stationary and the other part being connected to the brake-setting block and 130 movable toward the stationary part, whereby all of them act in the same line to withdraw

the brake-setting block when energized by polyphase currents.

5. The combination with the movable member or members of a friction-brake, of means for automatically setting said brake, and a brake-releasing means comprising a plurality of polyphase magnets arranged in tandem and provided with armatures that are con-

nected to the brake-setting means so as to act in the same line in opposition thereto. ¹⁰

In testimony whereof I have hereunto subscribed my name this 11th day of May, 1899.

EGBERT M. TINGLEY.
